UNITED STATES PATENT OFFICE.

JOHN F. O'CONNOR, OF CHICAGO, ILLINOIS, ASSIGNOR TO WILLIAM H. MINER, OF CHAZY, NEW YORK.

FRICITION DRAFT RIGGING.

Application filed February 16, 1920. Serial No. 358,991.

To all whom it may concern:

Be it known that I, JOHN F. O'CONNOR, a citizen of the United States, residing at Chicago, in the county of Cook and State of Illinois, have invented a certain new and useful Improvement in Friction Draft Riggings, of which the following is a full, clear, concise, and exact description, reference being had to the accompanying drawings, forming a part of this specification.

This invention relates to improvements in friction draft riggings.

The object of the invention is to provide a friction draft rigging having very high combined frictional and spring capacity.

Other objects of the invention will more clearly appear from the description hereinafter following.

In the drawing forming a part of this specification, Figure 1 is a central vertical longitudinal elevation in part section of an improved draft rigging embodying my invention, the plan and section corresponding substantially to the broken line 1—1 of Figure 2. Figure 2 is a horizontal part sectional view, part top plan of the construction shown in Figure 1. Figure 3 is a vertical transverse sectional view corresponding substantially to the line 3—3 of Figure 2. Figure 4 is a detail perspective of one of the wedge elements employed with my improvements. Figure 5 is an elevational view of one of the plates secured to the sills. And Figure 6 is an elevational view of one of the combined yoke-acting and friction members.

In said drawing, 10—10 denote channel shaped center or draft sills of a railway car spaced the usual distance apart and to the outer faces of which are preferably secured flat reinforcing plates 11—11. A portion of a drawbar is indicated at 12, the same being operatively associated with the yoke-acting means by a short transverse key 13, the latter being adapted to be inserted through suitable slots 14—14 in the sills 10 and plates 11.

The improved mechanism includes, broadly, the following parts, that is, two yoke-acting members A—A, two series of wedge elements B—B on opposite sides of the center line, two series of laterally extending springs C—C on the outer sides of the sills, two series of bolts D, and station-

ary plates E—E on the inner sides of the sills. Each of the heavy plates E is fitted against the inner face of the corresponding draft sill 10 and has a series of outwardly extending rectangular lugs 15—15 seated in corresponding slots 16—16 provided in the draft sill and plate 11. The lugs 15 fit the slots 16 so that the heavy plates E are prevented from longitudinal movement. Each heavy plate E is provided with an upper longitudinally extending flat friction surface 17 and with a corresponding lower similar friction surface 18 as indicated most clearly in Figure 5. Intermediate the upper and lower friction surfaces 17 and 18, each plate E is provided with inwardly extended heavy bosses 19—19 and 20—20, the latter being at the ends and having sloping or inclined end faces 21—21. The intermediate heavy lugs 19 are of rectangular formation.

There are preferably three wedge elements B—B on each side of the center line and each of said wedge elements B is formed with oppositely inclined friction wedge surfaces 22 and 23 facing toward the corresponding center sill. At its center, vertically, each element B is provided on its outer side with a laterally extended rectangular lug 24 adapted to enter a corresponding rectangular opening 25 provided in the adjacent plate E. The openings 25 and lugs 24 are made such that the wedge elements B are confined to movement transversely of the sills and are prevented from longitudinal movement with respect thereto.

Each wedge element B is provided with a central longitudinally extending perforation 26 to accommodate a bolt D. The inner face of each element is recessed as indicated at 27 to accommodate a nut 28 screwed on the inner end of the corresponding bolt D. The outer end of each bolt D is provided with a corresponding nut 29 and washer 30, the corresponding spring C being mounted on the bolt between the washer 30 and the outer side of the draft sill or plate 11.

Each yoke-acting member A is provided at its forward end with an extension 31 slotted as indicated at 32 to accommodate the key 13 so that said members A—A move in unison with the drawbar in both buff and draft. Rearwardly of the extensions 31, the members A are provided with lat-

erally inwardly extended shoulders 33 against which the inner end of the drawbar is adapted to bear in buffing movements. Rearwardly of the shoulder 33, each member A is provided with upper and lower series of opposed inclined surfaces 122 and 123 adapted to cooperate with the respective inclined wedge faces 22 and 23 of the elements B. Each member A is cut away so as to provide a plurality of rectangular pockets 34-34 so that the member A slides over the lugs 19 and 20 of the corresponding plate E. Each member A is further provided on its outer side with flat friction surfaces 35 adapted to cooperate with the friction surfaces 17 and 18 of the corresponding plate E. At each end, on the outer side, each member A is provided with inclined shoulders 36 and 37 which are normally spaced from the inclined faces 21 of the plate E and which are adapted to contact with the latter to limit the movements of the members A in both buff and draft, as will be understood from an inspection of Figure 2.

The operation is as follows: Assuming an inward or buffing movement of the drawbar, both members A will be forced rearwardly by the drawbar. As the members A travel rearwardly, the friction wedge elements B will be forced laterally inwardly toward each other and toward the center line of the draft rigging, friction being generated between the sets of friction surfaces 22 and 122. Said lateral inward movement of the elements B will be yieldingly resisted by the springs C. In addition to the friction thus generated, friction will also be generated between the surfaces 35 of the members A and the surfaces 17 and 18 of the plates E. It is evident that the same action will obtain in draft as in buff except that the cooperating sets of inclined friction surfaces 23 and 123 will come into action instead of the surfaces 22 and 122. It will be noted also that, in the operation of the device, the lateral pressure on the draft sills is equalized from the outside and the inside so that there is no tendency to buckle or bend the center sills resulting from the lateral movement of the wedge elements B.

With the construction shown, it is evident that I may utilize all of the usual space allotted between the draft sills for the friction elements and the springs can be disposed outside of the sills in space that is not now generally otherwise used. It is also evident that the number of wedge elements B may be varied to obtain the desired capacity and various other changes and modifications may be made without departing from the spirit of the invention.

I claim:

1. In a friction draft rigging, the com-

bination with draft sills and a drawbar; of a laterally movable element, having a pair of oppositely extended wedge faces, said element being located between the draft sills; a spring disposed on the outer side of one of the draft sills to yieldingly resist lateral movement of said element; a heavy friction plate mounted on the inner side of said draft sill, on the outer side of which said spring is disposed, and a member longitudinally movable in both directions from its normal position and located between said element and said friction plate, said member being provided on one side with a pair of oppositely extending wedge surfaces cooperable with the wedge faces of said element for effecting lateral movement of the latter in both buff and draft, and on the other side with a friction face co-operating with said friction plate.

2. In a friction draft rigging, the combination with draft sills; of opposed transversely movable elements on the inner sides of the sills, said elements being adapted to move toward each other upon actuation of the draft rigging and each having a pair of oppositely extending wedge faces; members longitudinally movable in both directions each having a pair of oppositely extending wedge faces cooperable with those of said elements to effect the lateral movement of the latter; and springs located outside the sills adapted to yieldingly resist said lateral movement of said elements.

3. In a friction draft rigging, the combination with draft sills, of a series of independent wedge elements on the inner side of each draft sill, the wedge elements of one series being laterally movable relatively toward those of the other series upon actuation of the draft rigging; a laterally extending spring on the outside of the sill and a connecting bolt associated independently with each of said wedge elements; and a pair of longitudinally movable members having wedge faces cooperable with said wedge elements.

4. In a railway draft rigging, the combination with draft sills having heavy plates affixed to the inner sides thereof; of laterally movable wedge elements disposed within the sills, said wedge elements having outwardly extended lugs slidably mounted in corresponding openings in said plates; spring means yieldingly resisting lateral movement of said wedge elements; and longitudinally movable members interposed between said wedge elements and said plates, said members having wedge faces cooperable with the wedge elements and friction surfaces cooperable with said plates.

5. In a railway draft rigging, the combination with draft sills; of heavy plates disposed on the inner faces of said sills and held against longitudinal movement, said

plates having friction surfaces on their inner sides; of longitudinally movable yoke-acting members having outer friction surfaces cooperable with said friction surfaces of the plates, said members having a plurality of opposed sets of inclined wedge faces on their inner sides; a series of laterally movable wedge elements slidably mounted in said plates and having wedge faces cooperable with those of said members; and spring means disposed outside of the sills for yieldingly resisting lateral movement of said wedge elements.

6. In a railway draft rigging, the combination with draft sills; of heavy friction plates mounted on the inner sides thereof and provided with friction surfaces on their inner faces extending parallel to the sills; of a pair of yoke-acting members adapted to be operatively associated with the draw-bar, said members being each provided on its inner face with a series of opposed sets of wedge faces and on its outer side with a friction face cooperable with the corresponding heavy friction plate; a series of wedge elements associated with each of said yoke-acting members; and spring means for independently resisting lateral movement of said wedge elements.

7. In a railway draft rigging, the combination with draft sills; of plates disposed on the inner faces of said sills and held against longitudinal movement, said plates having a series of laterally extending openings therein; of two series of wedge elements disposed within the sills, one series on each side of the center line, each of said wedge elements having an outwardly extended lug seated within a corresponding opening in the adjacent plate; spring means for yieldingly resisting lateral movement of said wedge elements; and a pair of yoke-acting members, each of said members having outer friction surfaces cooperable with the friction surfaces of the plates and provided with a series of opposed sets of wedge faces on the inner side, said wedge faces being cooperable with the wedge elements.

8. In a railway draft rigging, the combi-

nation with draft sills; of stationary friction elements secured to the inner sides of said draft sills; longitudinally movable friction elements cooperable with said stationary friction elements and adapted to be moved longitudinally upon actuation of the drawbar; a spring resistance disposed on the outer side of each draft sill; a stationary abutment on the outer side of each draft sill and supported by the latter and against which the inner end of the corresponding spring resistance bears; and means, including a movable abutment on the outer end of each spring resistance, arranged to compress the spring resistances laterally inward toward the draft sills upon movement of said longitudinally movable friction elements.

9. In a friction draft rigging, the combination with draft sills and a draw-bar; of a laterally movable element having a pair of oppositely extended longitudinally arranged wedge faces, each of said faces extending transversely from edge to edge of said element, said element being located between the draft sills; a spring disposed on the outer side of one of the draft sills to yieldingly resist lateral movement of said element and a member movable longitudinally in both directions from its normal position, and located between said element and said draft sill on the outer side of which said spring is disposed, said member being provided on one side with a flat friction face and on the opposite side with a pair of oppositely extending wedge surfaces co-operating with the wedge faces of said element for effecting lateral movement of the latter in both buff and draft, each wedge face of said member being co-extensive in width with the co-acting face of said element, and extending transversely from edge to edge of said member.

In witness that I claim the foregoing I have hereunto subscribed my name this 7th day of Feb. 1920.

JOHN F. O'CONNOR.
